CLAIM

The ornamental design for a medical patch, as shown and described.

DESCRIPTION

The patent or application file contains at least one drawing executed in color. Copies of this patent or patent application publication with color drawing(s) will be provided by the Office upon request and payment of the necessary fee.

FIG. 1 is a front view of a medical patch of the present invention, also showing instructions for use.

FIG. 2 is a rear view of the medical patch of FIG. 1.

FIG. 3 is a top plan view of the medical patch of FIG. 1.

FIG. 4 is a bottom view of the medical patch of FIG. 1.

FIG. 5 is a right side view of the medical patch of FIG. 1.

FIG. 6 is a left side view of the medical patch of FIG. 1.

FIG. 7 is an enlarged 2-2 sectional view of the 1-1 portion of the medical patch of FIG. 1.

FIG. 8 is an enlarged 3-3 sectional view of the 1-1 portion of the medical patch of FIG. 1.

FIG. 9 is an enlarged perspective view of the 4-4 and 5-5 portions of the medical patch of FIG. 1 including shading of the ragged surface.

FIG. 10 is a bottom view of the medical patch of FIG. 1 with the pull tab raised.

FIG. 11 is a bottom view of the medical patch of FIG. 1 with the cover sheet partly removed; and,

FIG. 12 is a perspective view of the medical patch of FIG. 1 with the cover sheet partly removed.

The features shown in broken lines depict environmental subject matter only and form no part of the claimed design.
